UNITED STATES PATENT OFFICE

HENRY B. OATLEY, OF GREAT NECK, NEW YORK, ASSIGNOR TO THE SUPERHEATER COMPANY, OF NEW YORK, N. Y.

SUPERHEATER HEADER

Application filed January 15, 1927. Serial No. 161,395.

My invention relates to superheaters, especially those used in connection with locomotives, and is concerned more particularly with an improvement in the headers of such superheaters. It has for its purpose the provision of an improved header made of a solid steel forging.

It has been proposed heretofore to make headers of the general description to which my invention refers, of steel, but the method of manufacturing it was by casting. As will appear from the ensuing description and from the drawings, and as is well known to those familiar with this art, these headers are of a rather intricate design. It is the universal practice at the present time in this country and abroad to make these headers of cast iron, the grade of cast iron necessary being a particularly good one, the composition of which must be watched very closely. Attempts that have been made to make such castings of steel have been unsuccessful on account of the difficulty of avoiding blow-holes, to which cast steel is particularly liable.

The presence of such blow-holes is, of course, a very objectionable and serious matter. As far as I am informed, all attempts of using cast steel have, therefore, been abandoned.

The header made according to my invention is made from a single forged steel ingot. There will, therefore, be no blow-holes, the metal being very compact and satisfactory on account of the forging done on the ingot.

My invention is illustrated in the accompanying two sheets of drawings, in which Fig. 1 illustrates the application of the header to a locomotive superheater, the view being a section on line 1—1 of Fig. 2; Fig. 2 is a section on line 2—2 of Fig. 1; Fig. 3 is a front elevation; Figs. 4, 5, 6 and 7 show a modification; Fig. 4 being a fragmentary top view, Fig. 5 a fragmentary front view, Fig. 6 a section on line 6—6 of Fig. 5, and Fig. 7 a section on line 7—7 of Fig. 5; Figs. 8, 9 and 10 show another modification, Fig. 8 being a fragmentary top view, Fig. 9 a fragmentary front view, and Fig. 10 a section on line 10—10 of Fig. 9. Figs 11 and 12 show a further modification, these two views cor-

responding respectively to those of Figs. 6 and 5.

Referring first to Fig. 1, there is shown in this figure a flue sheet 1 into which are expanded the front ends of flues 2. The smokebox sheet of the locomotive is shown at 3. The header 4 for the superheater lies in the upper portion of the smokebox extending from one side to the other. Steam is supplied to it by the dry pipe 5. The superheater elements or units are shown at 6. These units are of the usual tubular form, each of them having four straight lengths suitably connected by return bends to form a continuous path for the steam. One end of each unit is secured to a chamber in the header receiving wet steam from the boiler and the other end to a chamber in the header delivering superheated steam to the steam pipe leading to the engine. All of this is in accordance with the usual standard well-known practice. The general disposition of the chambers in header, according to my invention, is also in accordance with present standard practice, as will be apparent from the ensuing description.

Referring next for a more detailed description of the header to Figs 2 and 3, it will be seen, from Fig. 2 particularly, that there are two chambers 4a and 4b respectively extending longitudinally through the header. Extending forward from the chamber 4a is a series of subsidiary chambers 4c; and extending rearward from the chamber 4b is a series of subsidiary chambers 4d. The chambers 4c and 4d are intermeshed in the usual way so that they alternate.

In accordance with my invention, I begin with a solid steel block. The chambers 4a and 4b are produced by boring. Their ends are closed, and for this purpose they are preferably threaded and plugs 4e—4e are screwed into these openings and then welded, as at 4f—4f.

The subsidiary or secondary chambers 4c are made by boring through the rear wall 4g and into the solid billet to a point short of chamber 4b. After they have been bored, the openings in the rear wall 4g are also closed, preferably by screwed and welded plugs.

The subsidiary chambers 4d are produced in a corresponding manner, these chambers stopping short of chamber 4a, and the openings in wall 4h being likewise closed by 5 screwed and welded plugs.

It will be understood that the closures for the holes spoken of above may be effected in any suitable or preferred manner.

To secure the superheater units or elements 10 6 to the header I employ means like those which have been used hitherto, that is, bolts and nuts 8 and clamps 7. This feature needs no description as it is well known. To accommodate the bolts 8 I bore the holes 9—9 15 through the partition walls between the subsidiary chambers 4c and 4d.

Holes 20—20 are bored from the underside of the header to communicate with the subsidiary chambers 4c and 4d, their arrangement being clear from Fig. 2.

10 is a connection for the saturated steam from dry pipe 5 and is welded into the opening 11, which has for this purpose been bored into the header 1 at the point 12, enlarged 25 for this purpose, the opening 11 intersecting and communicating with the chamber 4a.

Connections 13—13 for securing the steam pipes which are to carry the steam to the engine are suitably secured into openings in 30 the front wall preferably by welding.

It will be seen that my invention provides a steel header of dense steel free from blow-holes and defects. On account of the greater strength of steel, it can be made considerably lighter than a cast iron header of the same strength.

Referring next to the modification of Figs. 4 to 7, it will be seen that the billet is given a somewhat different form. In cross-section 40 it becomes more nearly square. The chambers 4a and 4b are bored in the upper half of the billet and have their ends closed as in the form first described. The subsidiary chambers 4c are made as follows: Using a suitable bore each of them is formed by boring from the rear side of the header at such a point that the subsidiary chamber will intersect and open into the main chamber 4a as at 4k. The depth to which this bore is used, however, must not be great enough to let the subsidiary chamber 4c intersect the chamber 4b as otherwise the steam would obviously flow directly into the chamber 4b without going through the superheater elements. 50 For this reason the second portion of the subsidiary chamber 4c is made by boring two holes 4m of smaller diameter side by side as most clearly shown in Fig. 5. These holes terminate short of the front wall of the header.

Each of the subsidiary chambers 4c is formed in this way.

The subsidiary chambers 4d are formed in a corresponding manner each intersecting and 60 opening into the chamber 4b at the point 4n

and the parts of these subsidiary chambers under the chamber 4a being formed by two channels 4p as clearly seen in Fig. 5. The holes 4q—4q for the superheater connections are bored from the bottom side of the header 70 as in the first instance.

It will be clear from an inspection of Figs. 6 and 7 that it is impossible in this case to bore holes through the header for the bolts. For this reason I use another common arrangement for securing the superheater elements to the header, that is, I machine slots 75 4r—4r in the bottom side of the header, these slots being T-shaped and extending from front to back of the header. The heads of the bolts are slid into these slots in the well known manner.

Connections 10 and 13—13 are made to this header in the same manner as in the form first described.

In the form illustrated in Figs. 8 to 10, one of the chambers, that is, the chamber 4a, is shown in the upper portion of the billet and the other, that is, 4b, in the forward portion. It will be noted that this arrangement is a 80 combination of the form first described and that shown in Figs. 4 to 7. The subsidiary chambers 4c communicating with the chamber 4a are bored into the header from the rear and intersect the header 4a at 4k as in 90 the first modification. They may, however, be of full size for their entire distance inasmuch as the location of the chamber 4b is different from the one shown in the first modification and there is no question of intersecting this chamber. They stop short of the 95 chamber 4b.

The subsidiary chambers 4d communicating with the chamber 4b are bored from the front. The full size bore is used up to the 105 point 4s and from there on a double smaller bore as in the first modification.

There is shown in this modification one variation with regard to the connection 10, and that is that it is placed at the top. This 110 can obviously also be used in connection with the principal form or the first modification. Vice versa, the connections 10 might in this second modification also be at the rear instead of at the top.

This second modification is equipped with T slots like the first modification.

In Figs. 11 and 12 is illustrated a modification of the subsidiary chambers. Where these extend under one of the cross-chambers 120 4a or 4b, their smaller size may be effected in a manner different from that described in connection with the first two modifications. The reduced portion, instead of being made of two bores of a diameter equal to the radius 125 of the larger bore, the centers of the three bores lying in a common plane, is here made by a single smaller bore, 4dd, whose center A lies below the center B of the large bore 4d. The top of the bore 4dd is lower than the top 130

of the two small bores in the first two modifications, and as a result the longitudinal chamber above it can be put a little lower than in the first modifications. This makes it possible to use a somewhat smaller billet. The 5 holes 20—20, which open into the bore 4dd, do so at the sides of the bore as will be clear from an inspection of Fig. 12.

The construction of the secondary chambers 10 opening into the chamber 4a and whose smaller bore extends under 4b, is similar to that described and will be understood without further words.

It will be obvious that some variations may 15 be made in the details of the header without departing from my inventive idea. My invention, as stated above, and as will now be clear, results in a steel header which is without all the defects which have hitherto made 20 the use of steel for this purpose impossible.

I claim:

1. A superheater header comprising a unitary forged steel block having two parallel cylindrical chambers, and provided with a 25 series of parallel subsidiary chambers at right angles to said first named chambers and each comprising a large cylindrical portion communicating with one of the first named chambers and a smaller cylindrical portion lying under the second of the first named chambers.
2. A superheater header comprising a unitary forged steel block having two parallel cylindrical chambers, and provided with a 35 series of parallel subsidiary chambers at right angles to said first named chambers and each comprising a large cylindrical portion communicating with one of the first named chambers and a smaller portion comprising 40 two parallel cylindrical bores extending under the second of the first named chambers.
3. A superheater header comprising a unitary steel block having two parallel cylindrical chambers and provided with two series of 45 parallel subsidiary chambers at right angles to said first named chambers, those of the first series intermeshed with those of the second series, each subsidiary chamber having a large and a small cylindrical portion, the 50 large portions of those of one set communicating with one of said first named chambers and the large portions of those of the other set communicating with the second of said first named chambers, the small portions of 55 each subsidiary chamber lying under that one of the first named chambers with which the large portion does not communicate.

HENRY B. OATLEY.
